UNITED STATES PATENT OFFICE.

CÉLESTE JOLY, OF LONDON, ENGLAND, ASSIGNOR OF THREE-FOURTHS
TO EDWIN JOSEPH RICHARDSON, BOYDELL GRAVES, AND BARNARD
ALFRED SPAULL, OF LONDON, ENGLAND.

APPARATUS FOR THE LIQUEFACTION OF AIR OR OTHER AERIFORM FLUIDS.

SPECIFICATION forming part of Letters Patent No. 718,572, dated January 13, 1903.

Application filed February 17, 1902. Serial No. 94,635. (No model.)

To all whom it may concern:

Be it known that I, CÉLESTE JOLY, a citizen of the Republic of France, residing at London, England, have invented a certain new and Improved Apparatus for the Liquefaction of Air or other Aeriform Fluids, of which the following is a specification.

This invention relates to an improved apparatus for the liquefaction of air and other aeriform fluids.

In my improved apparatus cooled compressed gas from a suitable source enters the outer end of an inlet series of coils of pipe arranged in a series of thermally-insulated chambers. The inner coil of the said series extends and opens into the interior of a fluid-tight vessel arranged in one of the said insulated chambers. This vessel is in communication at the top with the inlet of a pressure-maintaining valve, the outlet of which communicates with a coil, which also extends down the said chamber, at the bottom of which it is connected through a three-way passage with a thermally-insulated liquid-receptacle and with the inner end of an outlet series of coils, which extend through the insulated chambers above mentioned. By this means very advantageous results are obtained, the pressure of the compressed gas entering the inlet-coils being much lower than has been required with the apparatus heretofore known.

My said invention also comprises other improvements hereinafter set forth.

In the accompanying drawings, Figure 1 is a vertical longitudinal section, and Fig. 2 is a horizontal section of an apparatus constructed according to my said invention.

The compressed gas, whose heat of compression has already been absorbed, enters the apparatus through a pipe 1 and is cooled in a coil 11 in a thermally-insulated chamber 2. From the coil 11 the cooled gas passes to a coil 12 in another thermally-insulated chamber 3. From the coil 12 the gas passes on into a coil 13 in a thermally-insulated chamber 4, where it is still further cooled. From the coil 13 the cold gas passes into the upper end of a coil 14, which extends from the top to near the bottom of a fluid-tight thermally-

insulated vessel 5. The gas liquefies in this coil, which is open at its lower end, and passes into the vessel 5. The heat of condensation forces a portion of this liquid to evaporate, thereby augmenting the pressure in the said vessel. The vessel 5 is in communication at the top with the inlet side of a pressure-maintaining valve 6, provided with an insulating-cover 7. The gas which escapes through this valve expands in a coil 15, also extending from the top to the bottom of the vessel 5. This expansion produces intense cold, which causes most of the gas to liquefy and pass through the downwardly-extending branch of a three-way connection 16 and through a valve 8 to a thermally-insulated receptacle 9, where it may be collected. The gas which does not liquefy passes through the other branch of the connection 16 to the compressor through outlet-coils 17, 18, and 19, respectively, arranged in the chambers 4, 3, and 2, leaving the apparatus through the pipe 10. With such an arrangement the liquid is produced at the atmospheric pressure. The space between the inlet and outlet coils in the chambers 2 3 4 is filled with a material of high thermal conductivity, such as copper or other suitable metal or solid in a subdivided condition, so as to facilitate the transfer of heat between the said coils, or, if desired, a liquid of good thermal conductivity which freezes at a very low temperature, such as a solution of chlorid of calcium in alcohol, can be employed for this purpose. If desired, a cock can be provided for drawing off the liquid air in the vessel 5 directly.

Having thus fully described my invention, what I claim as new, and desire to secure by Letters Patent, is—

1. The combination, in apparatus for liquefying air and aeriform fluids, of thermally-insulated chambers, inlet-coils of pipe with connections so as to form a continuous series contained in and extending through said insulated chambers, an inner thermally-insulated vessel, a coil of pipe arranged in said vessel and connected with said series of coils and opening within said vessel, a pressure maintaining valve having its inlet side in

communication with the interior of said vessel, a coil of pipe connected with the outlet side of said valve and extending through said vessel, a three-way connection at end of last-mentioned coil, a receptacle for the collection of the liquid, and a series of outlet-coils of pipe extending through said insulated chambers for the outlet of the cold fluid which has passed through the valve and which has not been retained in the liquid form, substantially as described.

2. The combination, in apparatus for liquefying air and aeriform fluids, of thermally-insulated chambers, inlet-coils of pipe with connections so as to form a continuous series contained in and extending through said insulated chambers, an inner thermally-insulated vessel, a coil of pipe arranged in said vessel and connected with said series of coils and opening within said vessel, a pressure-

maintaining valve having its inlet side in communication with the interior of said vessel, a coil of pipe connected with the outlet side of said valve and extending through said vessel, a three-way connection at the end of 25 the last-mentioned coil, a receptacle for the collection of the liquid, a series of outlet-coils of pipe connected at its inner end to said three-way connection and extending through said insulated chambers, and a substance of 30 good thermal conductivity arranged in said insulated chambers between said inlet and outlet coils, substantially as described.

In testimony whereof I have hereunto set my hand in presence of two subscribing witnesses. 35

CÉLESTE JOLY.
